ABSTRACT OF THE DISCLOSURE

An electromagnet having a U-shaped core comprising a first portion defining a first pole and a second portion defining second and third poles symmetrically disposed around a fourth shaded pole, and an electromagnetic operator comprising the electromagnet, an electrical winding on the first portion of the core and a keeper armature disposed on the first pole for fulcrum action and having a contact end extending over the second portion of the core to contact the fourth pole when the winding is energized.

BACKGROUND OF THE INVENTION

The present invention pertains to an electromagnet and particularly to an electromagnet utilizing a symmetrical arrangement of shaded and unshaded poles.

Many attempts have been made to prevent armature bounce and vibration, sometimes referred to as chatter or buzzing, in electromagnetic operator systems. The conventional manner in which such vibration is eliminated is to provide a shaded pole along with a single unshaded pole such that the flux sensed by the armature never drops to zero. That is, when the coil of an electromagnet is energized from an A.C. source, the composite flux from the shaded and unshaded poles is never zero due to the phase displacement of the flux at the shaded pole. This use of a shaded pole with an unshaded pole is effective in reducing the vibration obtained when an unshaded pole is utilized by itself; however, this combination still provided more vibration than is desirable in the operation of electromagnetic switches, valve operators, and other sensitive devices.

Along with their undesirable vibration characteristics conventional electromagnets are disadvantageous in that if the shaded and unshaded poles are laterally spaced there is an unbalanced pull on the armature, and whether the poles are laterally spaced or aligned with the longitudinal axis of the armature, imbalance exists and is aggravated by variations in spring bias on the armature and foreign particle deposits on the pole faces.

SUMMARY OF THE INVENTION

Accordingly, it is an object of the present invention to construct an electromagnet that substantially eliminates armature vibrations.

Another object of the present invention is to eliminate vibrations in an electromagnetic operator by symmetrically disposing a plurality of unshaded poles around a shaded pole.

A further object of the present invention is to prevent armature bounce and vibration in an electromagnetic operator by constructing the electromagnet as a four-pole piece with one pole acting as a fulcrum for the armature.

The present invention has another object in that armature vibrations in an electromagnetic operator are eliminated by disposing a plurality of unshaded poles sym-

2

metrically with respect to a shaded pole and the armature.

The present invention is advantageous over conventional electromagnetic operators in that armature bounce and vibration is substantially eliminated to thereby provide accurate operation of the devices to be operated upon.

The present invention is generally characterized in that an electromagnet comprises a first leg defining a first pole, a plurality of second legs symmetrically disposed around the first leg to define a plurality of second poles, and shading means disposed around the first leg and an electromagnetic operator comprises the electromagnet described above in combination with an armature disposed so as to contact another pole of the electromagnet as a fulcrum and extending over the first and second poles.

Other objects and advantages of the present invention will become apparent from the following detailed description of the accompanying drawings.

BRIEF DESCRIPTION OF THE DRAWINGS

FIG. 1 is a view in perspective of an electromagnetic core of the present invention.

FIG. 2 is a front elevational view, partially in section, of an electromagnetic operator of the present invention.

FIG. 3 is a side elevational view in section of the electromagnetic operator of FIG. 2 in a closed position.

DESCRIPTION OF THE PREFERRED EMBODIMENTS

FIG. 1 is a perspective view of a core 10 of an electromagnet constructed in accordance with the present invention. Core 10 is substantially U-shaped and comprises two upstanding portions, indicated generally as 12 and 14, connected together by a flat bottom portion 16. Portion 12 defines a pole face 18 that extends the entire width of core 10, and portion 14 is separated into three legs 20, 22, and 24 each defining a pole face 26, 28, and 30, respectively, with the areas of pole faces 26 and 30 being equal.

Core 10 may be made of any conventional soft magnetic material suitable for use in electromagnets, and the specific shape of core 10 shown in FIG. 1 is not meant to be limiting in that the important criterion is that the outside legs of portion 14 be symmetrically spaced from the center leg as will be explained hereinafter.

An electromagnetic operator utilizing core 10 is shown in FIG. 2 and is supported by a right angled frame 32, preferably constructed of material not susceptible to being magnetized in order to prevent the establishment of diversionary magnetic fields. Core 10 has a circular recess 34 adapted to accommodate the flattened head of a protrusion 36 which extends from frame 32 through a bore 38 aligned with recess 34 in core 10 in order to secure core 10 to frame 32.

Portion 12 of core 10 has an electrical winding 40 wound therearound, which winding is adapted to be connected to any conventional source of varying electrical energy such as an A.C. voltage source. Pole 18 associated with portion 12 of core 10 acts as a fulcrum for a keeper armature 42 which is biased at one end by a spring 44

60 that may be connected with any stationary structure such as frame 32. Armature 42 may be constructed of any conventional easily magnetizable material and is elongated in order to permit contact with pole 28. While armature 42 is shown as being planar, it should be noted that armature 42 may have any shape convenient to the operation of the electromagnetic operator. For instance, if greater movement is required of armature 42 upon energization of the electromagnetic operator, the spring biased end of armature 42 may be extended or the end of armature 42 that contacts pole 28 may be offset to require greater movement to cause contact. Armature 42

65

70

may also be shaped to accommodate the device operated to provide snap action.

The width of armature 42 is approximately equal to the width of core 10, as can be seen from FIG. 3, and a semi-spherical bulge or nipple 46 is pressed out at the contact end of armature 42 to provide equalized air gaps between poles 26 and 30 and armature 42 and firm contact with pole 28. A leaf spring 48 having an offset end 50 is secured to frame 32 by a screw 52 such that offset end 50 is in contact with armature 42 directly above pole 18 to aid in the fulcrum action thereof. A shading ring 54 is disposed around leg 22 and may be made of any conventional shading material such as copper.

With further reference to FIG. 3, which is an elevational sectional view of portion 14 of core 10 and armature 42 in a closed position, it is seen that poles 26 and 30 are symmetrically spaced from shaded pole 28, and due to this symmetry and the configuration of armature 42 the horizontal components of the magnetic flux at poles 26 and 30 are equal and opposite in their effect on armature 42.

The operation of the electromagnetic operator of the present invention will be described with respect to FIGS. 2 and 3 and as operating a valve (not shown). When the electromagnetic operator is in an unenergized state, armature 42 is forced away from portion 14 of core 10 by bias spring 44 which may be disposed in tension between a stationary portion of the valve and the operating end of armature 42. The distance between armature 42 and portion 14 of core 10 may be controlled by providing an independent stop for armature 42, by designing leaf spring 48 to act as a stop due to abutment with armature 42 or by balancing the weight of armature 42 with the force of bias spring 44. In any case, in the unenergized state bias spring 44 forces the operating end of armature 42 down to, for instance, close the valve.

Upon the energization of coil 40 by an alternating current source for instance, which energization may be caused by the closing of an electrical switch either manually or automatically in response to a condition of a system of which the valve is a part, the current through coil 40 cause magnetic flux to be established in core 10. This magnetic flux, which is concentrated at poles 18, 26, 28, and 30 magnetizes armature 42 and pulls the contact end down so that nipple 46 contacts shaded pole 28. The initial downward force on armature 42 is provided by unshaded poles 26 and 30 because shading ring 54 delays the magnetic flux concentrated at pole 28. Due to their symmetry with respect to shaded pole 28 and armature 42 and their equal area pole faces, unshaded poles 26 and 30 prevent lateral movement of armature 42 and reduce the normal tendency of the armature to bounce or slide on the electromagnet.

The delay or phase displacement of magnetic flux at shaded pole 28 caused by shading ring 54 permits armature 42 to be in firm contact with core 10 throughout each entire cycle of alternating current energizing coil 40. That is, the phase displacement of magnetic flux permits flux to be concentrated at pole 28 when the alternating current is at a zero level.

Variations in spring forces and loads at the end of armature 42 will not adversely affect the operation of the electromagnetic operator of the present invention because the symmetry of unshaded poles 26 and 30 with respect to armature 42 and shaded pole 28 causes armature 42 to be subjected to equal and opposite lateral magnetic forces at all times; and, consequently, any variation of force in the longitudinal direction need only be overcome by the vertical components of the flux at the poles of portion 14 of core 10. Vertical bounce of armature 42 is also eliminated due to the extension of the contact end of armature 42 directly over unshaded poles 26 and 30, and the strong magnetic fields at these poles provide firm control of the armature to secure the contact of nipple 46 with shaded pole 28.

With respect to operation of a valve, the operating end of armature 42 moves up upon energization of the electromagnetic operator to force nipple 46 to contact pole 28, and the operating end may be connected directly or through mechanical linkage to a valve member to open the valve.

The shape of the armature to be used with an electromagnetic operator constructed in accordance with the present invention, should be considered in designing the leg position of the core; however, when the armature has a longitudinal axis in parallel with the spacing between the two portions of the core and passing through the shaded pole, it is sufficient to dispose the unshaded poles symmetrically with respect to this axis. The most important criterion in constructing an electromagnetic operator in accordance with the present invention is that the shaded and unshaded poles be disposed symmetrically with respect to each other and to the longitudinal axis of the armature.

The present invention, thus, provides an electromagnetic operator that may be used with sensitive devices such as switches and valves and substantially eliminates the normal armature vibrations associated with conventional electromagnetic operators.

Inasmuch as the present invention is subject to many variations, modifications and changes in detail, it is intended that all matter contained in the foregoing description or shown in the accompanying drawing shall be interpreted as illustrative and not in a limiting sense.

What is claimed is:

1. An electromagnetic operator comprising a core having a first portion defining a first pole and a second portion including first, second and third legs defining second, third and fourth poles, respectively; an electrical winding disposed around said first portion of said core and adapted to be connected to an energization source;

shading means disposed around said first leg of said second portion of said core;

armature means disposed to contact said first pole as a fulcrum and extending over said second portion of said core;

said third and fourth poles being disposed symmetrically about said second pole whereby said armature means may be pulled in without vibration when said electrical winding is energized.

2. The invention as recited in claim 1 wherein said armature means has a longitudinal axis, and said third and fourth poles are disposed symmetrically with respect to said longitudinal axis.

3. The invention as recited in claim 2 wherein said armature means has a bulge in the end extending over said second portion for contacting said second pole when said electrical winding is energized.

4. An electromagnetic operator comprising:

a unitary core having a first portion defining a first pole and a second portion having a plurality of legs defining a plurality of second poles and a third pole; energizing means coupled with said core;

shading means disposed around one of said plurality of legs; and

armature means disposed so as to be in contact with said first pole and having a contact end extending over said second portion of said core and an operating end, said first pole acting as a fulcrum for said armature means;

said second poles being symmetrically disposed around said third pole whereby said armature means may be pulled in without vibration.

5. The invention as defined in claim 4 wherein bias means is connected with the operating end of said armature means.

6. The invention as recited in claim 4 wherein said shading means is disposed around the leg defining said third pole.

7. The invention as recited in claim 4 wherein said armature means has a longitudinal axis, and said plurality of second poles are disposed symmetrically with respect to said longitudinal axis.

8. A unitary core for an electromagnet comprising:
a first upstanding portion defining a first pole; and
a second upstanding portion spaced from said first upstanding portion by a bottom portion and defining second, third and fourth poles,
said second and third poles being disposed symmetrically about said fourth pole and equidistant from said first pole.

9. An electromagnet comprising:
a generally unitary U-shaped core having a first upstanding portion spaced from a second upstanding portion by a bottom portion, said first upstanding portion defining a first pole and said second upstanding portion having first, second and third legs defining second, third and fourth poles, respectively;
said third and fourth poles being disposed symmetrically about said second pole and equidistant from said first pole; and
a shading ring surrounding said first leg for causing phase displacement of magnetic flux at said second pole.

5

10. The invention as recited in claim 9 wherein an electrical winding is disposed around said first upstanding portion for energizing said electromagnet.

cally about said second pole and equidistant from said first pole; and
a shading ring surrounding said first leg for causing phase displacement of magnetic flux at said second pole.

10. The invention as recited in claim 9 wherein an electrical winding is disposed around said first upstanding portion for energizing said electromagnet.
